HEAT-EXCHANGE APPARATUS

Application filed October 26, 1926. Serial No. 144,233.

The present invention relates to heat exchange apparatus and more particularly to apparatus of this character well adapted for the purpose of usefully recovering heat from the residuum resulting from the refining of 5 crude petroleum oils.

The object of the present invention is to reorganize and improve apparatus of this character in order to adapt it particularly to 10 the problems encountered in the handling of petroleum oils.

With this and other objects in view the various features of the invention, all of which contribute to the new and improved result, 15 will be more fully described hereinafter. Incidentally, certain of the features of the present invention are adapted for the improvement of heat exchange apparatus in general in addition to improving the efficiency and operation of such apparatus in 20 connection with the refining of petroleum oil.

In the accompanying drawings illustrating the preferred form of the invention,

Fig. 1 represents an elevation partly in 25 section of a heat exchange apparatus embodying the features of the invention;

Fig. 2 is a sectional elevation of the shell and baffles foreshortened in length; and

Fig. 3 is a cross section of the shell upon 30 the line 3—3 of Fig. 2.

The heat exchanger shown in the illustrated embodiment of the invention comprises a tubular shell 10 having annular attaching flanges 12 and 14 at opposite ends. 35 Each attaching flange is riveted to the shell as indicated at 16. At one end the shell is provided with a tube supporting head 18 which may be a casting of iron or steel provided with an attaching flange 20 connected to the flange 14 by bolts 22. The head 18 is provided with an integral web 24 in which are mounted a series of tube bundles indicated respectively at 26. Each of these tube bundles, as will be evident, consists of a series of relatively thin wall tubes adapted 45 for the intercommunication of heat between the space surrounding the tubes and the interior of the tubes. The web 24 is provided upon the tube side with integral partitions 49 or baffles 28 which cooperate with sheet baf- 50 fles 30 to provide longitudinal passes for the hot oil residuum. On the opposite side the web is provided with integral partitions 32 which provide passages for directing the flow of one or more cooling mediums through the 55 interior of the tubes, the cooling medium or mediums passing lengthwise of the tubes through the chambers or passages 34 formed at one side of the web 24, as indicated clearly in Fig. 1. Each tube bundle is connected at 60 the end opposite the supporting head to a separate floating head 36 which is provided with a cover member 38 for sealing the tube bundle and returning the flow of cooling medium from a portion of the tubes in the 65 bundle in a counter direction through the remaining tubes. With this connection it will be evident from an inspection of Fig. 1 that the upper partition 32 causes a cooling medium to enter the lower tubes in the upper 70 bundle and flow through these tubes from right to left. Thereafter the chamber formed in the upper floating head returns the cooling medium through the remaining tubes in the upper portion of the bundle, the direction 75 of flow being from left to right, this operation being duplicated in the remaining tube bundles. Due to the control of the flow, the tubes in each bundle expand and contract in substantially the same manner so that undue strains are not imposed on either the floating heads or the unitary tube supporting head. In addition to the relatively thin sheet baffles 30 extending lengthwise through each tube bundle, additional baffles 40 are interposed between the tube bundles, these baffles being preferably of zig-zag formation in order to create a surge in the liquid flowing about the exterior of the tubes and cause a thorough intermingling of this liquid with that portion of the tube bundle supported above each baffle 40. Each of the baffles 40 is also provided with an extension 42 projecting between each two adjacent floating heads and serving as a support upon which each floating head thereabove may slide freely during the expansion and contraction of the tube bundle to which it is connected. The zig-zag baffles are supported by angle brackets 44 spaced at 80 the desired intervals and connected to in- 85 90 95 100

ner wall sections 48. In addition to being supported by angle brackets 44, both the zig-zag baffles and the extensions 42 are rigidly connected along opposite edges by 5 welded areas indicated at 43. In the case of the zig-zag baffles, these welded areas connect the edges of the baffles with the inner wall section, whereas in the case of the extensions the welded areas are formed upon the 10 outer shell. With this construction it will be evident that the baffles are rigidly retained in the proper relation. As indicated, the inner wall sections are spaced from opposite sides of the shell to provide a double wall en- 15 compassing an insulating space. Each of these sections, as indicated in Fig. 3, comprises a straight portion with out-turned upper and lower flanges 50 which engage the outer sides of the straight baffles 30 between them, the flange portions of the sides and the edges of the baffles being rigidly connected by bolts 52. This construction provides a rigid and accurate spacing of the baffles with relation to the shell and to one another. Fur- 20 thermore the space encompassed by the double side wall serves to insulate the relatively hot oil passing through the intertubular space and prevent loss of heat through the walls of the shell. Furthermore the rela- 25 tively hot oil which may be an active corrosive agent is separated from the surface of the shell, and corrosion of the shell thereby is accordingly minimized. The wall sections 48 terminate prior to one end of the shell, 30 affording a space for the movement of the floating heads and in addition permitting a partial withdrawal of the shell with relation to the tube bundles until the baffle ends contact with the floating heads. This partial 35 withdrawal may be accomplished by discon- 40 necting the flanges 14 and 20 and carrying the shell lengthwise of the tubes. In this position, access to the space surrounding the tubes may be obtained, and if so desired the 45 sealing gasket between the flanges 14 and 20 may be replaced. The shell is provided at one end of the wall section with vertically disposed angle brackets 53 which serve to close one end of the insulating space encom- 50 passed by the inner wall sections, thus forming a still body of oil in this space which serves as an excellent insulating medium. In addition to the insulating space extending throughout the sides of the shell, the latter 55 at its upper and lower portions is provided with a series of transverse angle bars 60 which, as indicated clearly in Figs. 2 and 3, extend across the top and bottom of the shell and partially throughout the sides to points 60 adjacent the upper and lower baffles. These transverse angles not only reinforce the shell but also serve as baffles tending to interfere with the flow of oil lengthwise of the shell and adjacent to the surface, thus providing 65 an insulating effect due to the relatively

slower moving body of oil throughout the upper and lower areas of the shell. The wall sections and interconnected baffles are rigidly supported upon the side walls of the shell by parallel angle brackets 62 extending 70 lengthwise of the walls above and below the series of baffles, these angle brackets being riveted or otherwise connected to the walls of the shell in any desired manner.

The baffle construction as outlined facil- 75 tates the erection and assembly of the completed heat exchanger, and permits a much closer and more compact arrangement of tubes and baffles than could otherwise be secured. In actual practice the zig-zag baffles 80 40 together with the intermediate straight baffles 30 are assembled and rigidly connected to the inner side wall sections 48. In forming this assembly the extensions 42 are riveted to the ends of the baffles 40 and extend 85 therefrom, supported only along the riveted areas. This assembly is then inserted lengthwise within the shell, the position being controlled by the upper and lower longitudinal brackets 62 which serve as tracks or guides. 90 At the same time the upper and lower sheet baffles 30 are loosely assembled therewith. The entire assembly may then be connected to the brackets by bolts or rivets, as indicated at 52. Having thus rigidly assembled the 95 above structure within the shell, the extensions 42 are then warped, if necessary, into accurate alignment with one another and with the shell, and rigidly welded to the shell at opposite edges to preserve the spaced 100 relationship. Thereafter the floating heads are mounted upon or in proper relation to the extensions and the shell, the head casting connected to the opposite end of the shell 105 and the tubes inserted and flanged in place. 110

The apparatus is so designed that the hot liquid from which heat is to be extracted enters the intertubular space at the upper portion of the shell, and after being repeatedly passed back and forth lengthwise of the tubes is discharged at the lower portion of the shell. In this manner the flow follows the path of least resistance, the hot residuum as it is cooled by its passage lengthwise of the tubes descending by gravity to the bottom 115 of the shell. In the illustrated embodiment of the invention, the inlet for hot oil is indicated at 61 and the outlet is indicated at 65. The inlet is formed integral with the casting 18 and is provided with a bolting flange 63. It communicates with the intertubular space between the upper baffle and the top of the shell. The outlet is formed in a similar manner with a bolting flange 64 and communicates with the lowest portion of the intertubular space below the lowermost baffle. With this construction the hot oil first flows from right to left above the upper baffle, thence downwardly between the end of the baffle and the adjacent floating head, and then 120 125 130

from left to right above the zigzag baffle 40 in contact with the lower half of the upper tube bundle. Thereafter upon reaching the end of the zig-zag baffle the oil discharges downwardly and the operation is repeated. 5

With this construction the heat is effectually extracted from the hot residuum before the latter is discharged from the outlet 65. In the usual practice the connection from the outlet extends upwardly to a point at least as high as the upper portion of the shell, thus insuring that the shell at all times shall be completely filled with hot liquid. It will furthermore be evident that both of the connections from the hot oil are formed in the head casting, in this manner permitting the shell to be disconnected and partially withdrawn without requiring that the pipe connections which communicate with the inlet 10 and outlet be dismantled. The end of the shell opposite the tube support is closed by a cover member 70 provided with a bolting flange 72 which is connected with the shell flange 12 by bolts 74. The space within the cover 70 may be sealed by a gasket 76 of any desired type. Upon removal of the cover, access to the interior of the tubes may be had through a series of plugs 78, each threaded within the cover 38 closing a floating head. 15

By removing each of the plugs 78 and connecting a pressure line with the opening, the interior of the tubes may be cleaned or washed out very simply. By utilizing the floating head as a connection for the pressure line, a series of tubes may be cleaned interiorly at one time without the necessity of individually connecting the line to separate tubes. As will be evident, the connection of a pressure line to plug 78 accompanied by 20 an opening of the proper plug 110 in the cover 87 determines which half of the tube bundle shall be flushed out. In addition to the means for cleaning the interior of the tubes, the shell 10 adjacent the flange 12 is provided 25 with a series of bosses 80, each provided with a removable plug 82 which form openings, permitting access to the space surrounding the tubes for any purpose which may be desired. These openings or peep-holes, as indicated, are spaced at uniform intervals about the circumference of the shell adjacent the floating heads and the connection of the tubes thereto. 30

The flow of cooling medium through the interior of the tubes is controlled through a series of guiding partitions formed both upon the unitary tube support and upon a detachable cover member. As indicated more particularly in Fig. 1, the integral partitions 32 projecting from the web 24 cooperate with ribs 85 formed integral with a cover member 87 to provide passages for properly controlling the flow of cooling medium with respect to different tube series and bundles. For the purpose of cooperating with the guiding partitions, the tube supporting head 18 is provided with a series of inlet and outlet connections disposed in the proper relation to give, in combination with the cover member, any desired character of flow. For example, as shown in Fig. 1 of the drawings, an inlet nozzle 90 is formed at the lowermost portion of the head and an outlet nozzle 92 is formed upon the opposite side of the head slightly above. In like manner an additional inlet nozzle 94 and a third nozzle, not shown, are located at spaced intervals upon the head and cooperate with outlet nozzles 96 and 98, as indicated in dotted lines. If all of these nozzles are connected to sources of cooling fluid flow, each cooling medium will make two passes through the tube. In other words, each cooling medium will pass in one direction through half of the tubes in a bundle, and will thereafter return through the remaining half of the tube bundle located above the separating baffles. With all of the nozzles connected for operation, the cover member will be provided with a series of partitions 85 equal in number to the partitions 32 to form a series of closed chambers communicating only with the nozzles and the interior of the tubes. In the construction shown in Fig. 1, the cover member is adapted for controlling the flow of two cooling mediums, one medium, such as water, being delivered through the nozzle 90 and discharged through the nozzle 92 after passing twice through the tubes, and a second medium, such as cold charge oil, being delivered through the nozzle 94 and discharged through the nozzle 98 after passing four times through the interior of the tube series. With this character of flow, the outlet nozzle 96 and the upper inlet nozzle (not shown) are closed off, the charge oil being directed from the chamber 100 into the chamber 102, as indicated by the arrow in Fig. 1, through an open passage formed about the end of one of the partitions 32. This passage is preferably formed by a series of separate spools or bosses 104 extending from the cover member and contacting with enlargements 106 formed upon the free end of the partition, the spaces between these bosses providing a passage for the oil, as will be evident. The interior of the enlargements 106 is threaded to provide for the reception of retaining bolts 108 which rigidly connect the cover member, intermediate the edge, to the supporting head. The purpose of these intermediate bolts, which extend across the cover member intermediate the edges, is to insure a close joint between the cooperating ribs 32 and 85 and prevent any intercommunication between the closed chambers. Thus, if water is used as one cooling medium and oil as a second, there is no possibility of communication or leakage of water into the oil chamber, or vice versa. From an inspection of the drawings it will be evident that by revers- 120

130

ing the cover member and properly connecting the cooling medium inlets and outlets, a variation of the path of flow may be effected without altering the construction; or in other words, one medium may be caused to pass four times through the lower banks of tubes, and a final cooling medium twice through the upper bank of tubes instead of the path of flow hereinbefore described. It will also be evident that by providing different cover members, any desired character of flow may be secured. The cover member, as indicated, is provided with a series of plugs 110 threaded therein which communicate with the several chambers to provide for access thereto and cleaning of the chambers in the interior of the tubes as previously described. In addition, the head 18 adjacent the web 24 is provided with a series of plugs 112 to close openings communicating with the intertubular space adjacent the web, these openings serving in conjunction with the similar openings located in the opposite end of the shell, to permit access for cleaning the interior of the intertubular space without dismantling the apparatus. The shell is reinforced about its outer periphery by a series of spaced angles 115 which extend circumferentially thereabout and are welded thereto by areas 116. The apparatus is normally supported in a horizontal position by feet or brackets 120, 121 mounted respectively on one end of the shell and the mid portion of the supporting head, these feet being connected to abutments 122, as indicated. With the construction as described, it will be evident that the supports for the apparatus as a whole are located in each case immediately beneath the regions of support for opposite ends of the tube bundles. For example, one end of the tube bundles is connected to the unitary web formed in the head casting beneath which is located the foot 121. The opposite ends of the bundles are supported by the individual floating heads, which in turn are supported by the extension slides 42 and the lower portion of the shell. These extension slides are rigidly welded to the shell in the region of the floating heads and immediately above the foot 120. The result is to support the entire assembly in a manner to prevent distortion or warping, either of the shell or the individual tubes constituting the bundles. Furthermore it will be evident that by virtue of this form of construction, each floating head with the portion of the tube bundle carried thereby is supported directly from the rigid shell rather than from the head beneath, the load being transmitted through the extensions 42 to the wall of the shell. Not only does this prevent distortion of the tubes, due to non-alignments of the heads, but in addition strains upon the tubes themselves, and the connection between the tubes and floating heads is greatly minimized, due to the fact that each head is per-

mitted to slide independently of every other head and on its own independent support.

As stated previously, the hot residuum enters the upper portion of the shell and flows downwardly, and the cooling medium entering at the lower portion of the shell flows upwardly and in a counter direction at all times to the flow of the hot residuum. The result of this construction is to provide a controllable, and if desired substantially constant temperature difference at all points of flow between the hot and cold mediums. As will be evident, this result is obtained through the employment of the longitudinal baffles separating the intertubular space into a series of longitudinal passes which cooperate with the partitions in the head controlling the flow of cooling medium through the tubes. For example, referring to the upper bundle of tubes, the cooling medium flowing through the lower half of the bundle, from right to left, encounters hot residuum flowing through the intertubular space from left to right. Thereafter, the flow of cooling medium is reversed by the floating head and passes through the upper half of the bundle, from left to right, where it encounters the still hotter medium flowing in the opposite direction. As will be evident from an inspection of Fig. 1, the tubes in opposite sides of each bundle are slightly inclined with respect to one another, permitting the introduction of the partitions 28 and the baffles 30 intermediate the bundle, these baffles forming hot liquid passes which coincide with the cooling medium passages formed by the partitions 32.

What I claim is:

1. Heat exchange apparatus comprising a plurality of tube bundles, a single unitary head connected with one end of all of the tube bundles, a floating head connected to the opposite end of each tube bundle, a horizontal shell enclosing the tube bundles and floating heads, and means rigidly connected with the shell adjacent the floating heads and forming a sliding support therefor.

2. Heat exchange apparatus comprising a plurality of tube bundles, a single unitary head connected with one end of all of the tube bundles, a floating head connected to the opposite end of each tube bundle, a horizontal shell enclosing the tube bundles and floating heads, and a series of partitions connected rigidly with the shell and supporting the free ends of the tube bundles and connected floating heads in a manner to permit sliding movement thereover.

3. Heat exchange apparatus comprising a plurality of tube bundles, a single unitary head connected with one end of all of the tube bundles, a floating head connected to the opposite end of each tube bundle, a horizontal shell enclosing the tube bundles and floating heads, means for supporting each floating head from the shell in a manner to permit

sliding movement independent of the other heads, and means for supporting the shell in the region of support for the floating heads.

4. Heat exchange apparatus comprising a series of separated baffle members, means for rigidly connecting the baffle members in spaced relation, a shell, means for supporting the baffle assembly within the shell, a series of tube bundles extending longitudinally within the baffle assembly, a unitary support for one end of all of the tube bundles, a floating head connected to the opposite end of each tube bundle, and means connected with the baffle assembly and shell for supporting each floating head and the adjacent portion of the tube bundle connected thereto.

5. Heat exchange apparatus comprising an elongated shell, a head connected to one end of the shell, a plurality of banks of tubes supported within the shell, means for directing cooling medium through the tubes, means for directing heating medium in a series of passes lengthwise of the exterior of the tubes, means for impeding the flow of the heating medium adjacent the shell, and inlet and outlet connections for the heating medium communicating with opposite sides of the head.

6. Heat exchange apparatus comprising an elongated shell, a head connected to one end of the shell and comprising a circumferential outer flange with an intermediate transverse web, a plurality of tubes connected to the web and extending lengthwise of the shell, a plurality of floating heads connected to opposite ends of the tubes, means for forming a series of passes lengthwise of the exterior of the tubes, inlet and outlet connections formed in the circumferential flange upon the tube side of the web, and inlet and outlet connections for cooling medium formed in the flange upon the opposite side of the web.

7. Heat exchange apparatus comprising a substantially horizontal casing closed at opposite ends, a plurality of tubes supported within the casing and extending lengthwise thereof, a unitary support connected to the tubes at one end, a series of independent floating heads connected to the tubes at the opposite ends, a series of baffle plates rigidly supported at their outer margins and interposed between the floating heads to form passes lengthwise of the exterior of the tubes and supports for the floating heads.

8. Heat exchange apparatus comprising a head provided with a unitary tube support, a series of banks of tubes connected to the support, a shell connected to the head and enclosing the tubes, a floating head connected to the opposite end of each bank of tubes, means connected to the shell for enclosing the floating heads, a baffle connected to the shell and extending lengthwise between each two adjacent banks of tubes and floating heads partway toward the unitary support, a cooperating baffle extending from the unitary sup-

port partway toward the floating head and intermediate each bank of tubes, and means for admitting heating medium to the intertubular space enclosed by the shell.

9. Heat exchange apparatus comprising an enclosing shell, a series of banks of tubes contained within the shell, means at opposite ends of the tubes for directing cooling medium therethrough, means for conducting heating medium to and from the space about the tubes enclosed by the shell, means for causing the heating medium to traverse lengthwise of the tubes, and impeding ribs extending inwardly from the shell and designed to retard the flow of heating medium adjacent the shell to provide an insulating effect.

10. Heat exchange apparatus comprising an enclosing shell, a series of banks of tubes contained within the shell, means at opposite ends of the tubes for directing cooling medium therethrough, means for conducting heating medium to and from the space about the tubes enclosed by the shell, means for causing the heating medium to traverse lengthwise of the tubes, inner wall sections spaced from the shell, and means for substantially preventing the flow of heating medium through the space between the shell and inner wall sections.

11. Heat exchange apparatus comprising an enclosing shell, a series of banks of tubes contained within the shell, means at opposite ends of the tubes for directing cooling medium therethrough, means for conducting heating medium to and from the space about the tubes enclosed by the shell, means for causing the heating medium to traverse lengthwise of the tubes, inner wall sections spaced from the shell, and means for closing the space between the shell and inner wall sections at one end.

12. Heat exchange apparatus comprising a shell, a plurality of banks of tubes supported within the shell and extending lengthwise, a unitary support for the tubes at one end, a floating head connected to each bank of tubes at the opposite end, means for conducting heating medium to and from the intertubular space enclosed by the shell, and means located in the annular space between the banks of tubes and shell for substantially confining the flow of heating medium to the region immediately adjacent to the tubes themselves.

13. Heat exchange apparatus comprising a series of banks of tubes, a unitary support connected at one end of the tubes, a floating head connected to each bank at the opposite end, means for enclosing all of the tubes, means for conducting heating medium to and from the enclosed space about the tubes, means for compelling the flow of heating medium in a series of passes lengthwise of the tubes and for directing the flow of heating medium from the space intermediate adjacent banks into the space encompassed by the tubes of each bank.

14. Heat exchange apparatus comprising a

supporting head, a plurality of tubes connected at one end to the head, a shell detachably connected to the head and enclosing the tubes, means for conducting heating medium to and from the interior of the shell, and a series of baffles connected to the shell to form passes lengthwise of the tubes, the baffles being constructed and arranged to permit disconnection and partial withdrawal of the shell from the head lengthwise of the tubes without disconnecting either the baffles or the tubes.

15. Heat exchange apparatus comprising a tubular shell, a head detachably connected to the shell at one end having a tube supporting member, a series of banks of tubes connected at one end to the member, a supporting head connected to the opposite end of each bank, a series of baffles connected to the shell and disposed alternately intermediate the upper and lower portions of each bank and between banks of tubes, the intermediate baffle extending partway toward the floating head and the adjacent baffle between the banks extending from between the floating heads partway toward the unitary support, connections between the baffles and shell, and means formed in the head for conducting heating medium to and from the interior of the space enclosed by the shell.

16. Heat exchange apparatus comprising a head, a plurality of tubes connected at one end to the head, a shell enclosing the tubes, connections between the shell and head, means for directing cooling medium through the interior of the tubes, means for conducting heating medium to and from the interior of the shell about the tubes, and means located at opposite ends of the intertubular space for gaining access to the space and cleaning the exterior of the tubes.

17. Heat exchange apparatus comprising a tubular head provided with an intermediate transverse partition, a plurality of tubes connected at one end to the partition, a series of floating heads connected at the opposite ends of the tubes, a shell connected to the head at one side of the partition and enclosing the tubes, inlet and outlet connections in the head upon the tube side of the partition for conducting heating medium to and from the space enclosed by the shell, a head detachably closing the opposite end of the shell, a cover member detachably connected to the head on the opposite side of the partition from the tubes, a series of partitions formed respectively on the partition and cover member to provide passages for the flow of cooling medium, and inlet and outlet connections formed in the head and communicating with the passages to provide a selective control for the flow of cooling medium.

18. Heat exchange apparatus comprising a head having a transverse tube support, a plurality of banks of tubes connected to the

support, a floating head connected to the opposite end of each bank of tubes, a shell connecting the head and enclosing the tubes, and a baffle of zig-zag formation extending lengthwise between adjacent banks of tubes substantially filling the space therebetween to confine the lengthwise flow of heating medium to the space encompassed by the tube bank.

19. Heat exchange apparatus comprising a shell, a head connected at one end of the shell having a tube supporting member, a plurality of banks of tubes connected to the member, a floating head connected to the opposite ends of each bank and having a sealed chamber directing flow of cooling medium through the interior of the tubes, means for introducing cooling medium into the opposite ends of the tubes, removable means affording access to the interior of each floating head for cleaning the interior of the tubes, and removable means at the opposite side of the tube supporting member cooperating with the first-mentioned means for cleaning the interior of the tubes.

20. Heat exchange apparatus comprising a shell, a head connected at one end to the shell having a tube supporting member, a plurality of banks of tubes connected to the member, a floating head connected to the opposite end of each bank and having a sealed chamber directing flow of cooling medium through the interior of the tubes, means for introducing cooling medium into the opposite ends of the tubes, a closure plug detachably connected to each floating head and affording access when removed to the sealed chamber in the interior of the head, and a cover member connected to the shell and enclosing the floating heads.
